SIGNALING SYSTEM

Frank Rowland Bridges, Needham, Mass., assignor to The Gamewell Company, Newton Upper Falls, Mass., a corporation of Massachusetts

Application May 27, 1936, Serial No. 82,085

5 Claims. (Cl. 177—369)

This invention relates to signaling systems and more particularly to so-called "auxiliary signaling systems" whereby a device for formulating code signals in a main circuit may be caused to operate from a station or stations associated with an auxiliary current path.

In systems wherein such an auxiliary current path is energized from the main circuit, and is therefore frequently referred to by the term "auxiliary loop," it is customary to provide an electromagnet with its winding serially connected in the main circuit. Such magnet is—under normal conditions—short-circuited or shunted by the auxiliary loop, and becomes energized upon interruption or impairment of the current path through that loop. Resultant from such interruption, signal formulating mechanism is caused to operate for the purpose of formulating code signals over the main circuit. Systems of this character are frequently referred to as being of "shunt type."

Shunt type auxiliary systems have heretofore been extensively and advantageously used although, in the course of such use, it has been found needful to restrict the resistance of the shunt loops to a distinctly minor fraction of the resistance of the magnet windings respectively shunted thereby. Such relationship of resistances was found necessary in order to minimize occasions when the shunted magnet would unintentionally become effectively magnetized.

It has also been found that unintended energizations of such shunted magnets may result from current surges in the main circuit of exceptional intensity, even when the shunt loop resistance is well within the limits ordinarily deemed to afford a conservative factor of safety.

An important object of this invention is to render systems of the character described immune from response to partial or complete energizations of such main circuit magnets throughout continued closed circuit effectiveness or unimpaired continuity of their respective shunt loops.

Another object is to render it practical for the resistance of shunt loops as described to equal more nearly or fully, or even to exceed, that of the current path through the magnets they shunt, without thereby rendering the respective systems more susceptible to signal formulating activity responsive to energizations of such magnets as may occur without impairment of the current path through the shunt loop.

Another object of this invention is to provide such a signaling system wherein effective ener-

gization of the main circuit magnet causes complete or partial isolation of the shunt loop from the main circuit and from parts or components thereof.

A further object of this invention is to provide a signal system of the character described wherein effective or functional energization of the main circuit magnet causes the formulation and manifestation of signals such as may indicate, in its vicinity, the occurrence of such magnet energization.

A still further object of this invention is to provide such a signal system wherein circuit conditioning occurs, concurrently with the initiation of operation of the signal formulating mechanism, for rendering the main circuit current path lower or substantially equal in resistance relative to its resistance prior to initiation of operation of the signal formulating mechanism.

For the attainment of the foregoing objects pursuant to a general aspect of this invention, there is associated with a movable part, which suitably governs activity of the main circuit signal formulating mechanism, electromagnetic structure including two windings. One of said windings is for association with the main current path for energization from the current source therefor and the other of said windings is for energizable association with a current path in shunt relationship to said first winding.

More specifically, the electromagnetic structure involves parts and their arrangement wherein by a certain functionally significant activation of said movable part will result, during a predetermined degree of the excitation of one of said windings, only during predetermined impairment of excitation of the other of said windings. For example, the structure may be so arranged and proportioned that the movable part will assume a position for causing activation of the releasing or tripping mechanism only when the excitation of a certain one of said windings is at least as great as a predetermined minimum at a time when the excitation of the other of said windings does not exceed a predetermined maximum; or, in certain embodiments of the invention, when the differential between the excitations of such windings exceeds a predetermined value.

For the attainment of the foregoing objects in accordance with one of the more specific forms or "species" of this invention, two electromagnet windings are applied and connected in such relationship that current flow of intended nor-

mal directions and intensities therethrough will cause each winding to oppose and substantially neutralize the other.

In accordance with another form or species of this invention, the movable part is magnetically retained against movement responsive to energization of one winding throughout intended energization of the other winding.

In accordance with still another form or species, the movable governing part is arranged for actuation responsive to energization of one winding, and a detent or other restraining means is provided for blocking such actuation of the governing part responsive to energization of the other winding.

In further practice of this invention, contact mechanism is associated with each of the foregoing specific forms or species and is arranged to function concurrently with the attainment of the releasing or tripping positioning of the movable part. Such functioning of the contact mechanism renders effective shunt paths around certain of the magnets, effects isolation or disconnection of the shunt loop from the main circuit, and/or alters the conditioning of current paths for effecting manifestation of so-called "local alarms" or indications.

Other characteristics of this invention will appear from a consideration of the following detailed description, taken in connection with the accompanying drawings forming a part of this specification. It should be understood, however, that the embodiments illustrated, though practical, are by no means the only embodiments which the invention may assume, wherefore the invention is not confined to any strict conformity with the showing of the drawings, but may be changed and modified in various particulars, so long as such changes and modifications make no material departure from the salient features of the invention.

Like characters of reference denote corresponding parts throughout all the views presented by the accompanying drawings, in which:

Figure 1 is a diagrammatic representation of an auxiliary signaling system embodying a specific form of this invention which is suited for certain operating conditions;

Figs. 2, 3, 4, 5, 6 and 7 are fragmentary representations of electromagnetic controlling means and certain electrical connections embodying other specific forms of this invention suiting same for different operating conditions;

Fig. 8 is a rear elevation of releasing mechanism suitable for association with the system of Fig. 1;

Fig. 9 is an isometric view of the releasing mechanism of Fig. 8, with certain parts broken away and displaced in the interests of more clearly disclosing operating structure;

Fig. 10 is a fragmentary view of certain parts of the releasing mechanism of Figs. 8 and 9;

Figs. 11 and 12 are respectively front and side elevations of the releasing mechanism of Figs. 8 and 9;

Figs. 13 and 14 are elevations of portions of the circuit controlling devices of Figs. 8, 9, 11 and 12; and

Fig. 15 diagrammatically indicates a manner of employing certain features of this invention with an auxiliary circuit having independent current supply.

System with differential windings

The signaling system indicated in Fig. 1 com-

prises a main circuit MC, an auxiliary or shunt loop SL and a local alarm or supervisory loop LA.

The main circuit MC comprises conductors for serially connecting the signal formulating devices or stations 21, 22, 23 and 24, together with the recording or manifesting device RD, across the terminals of a current source CS.

A signal formulator or signal formulating mechanism is serially included in the main circuit and is diagrammatically indicated as comprising a pair of normally closed signal formulating contacts 31, a code wheel 32 and a tracer or key break lever 33 for imparting (to the contacts 31) code signal formulating actuations representative of the contour of said wheel 32, so that rotation of this wheel may cause a response of the device RD recognizable as characteristic of the signal formulating station 21, which station, in the instance shown, would be recognized by manifestation of the code number 221.

Associated with the signal formulating mechanism just described, there may be electromagnetically controlled releasing or starting mechanism of suitable well known type, however, for convenience of illustration and description, it will be herein assumed that the releasing mechanism is of the type more fully indicated in Figs. 8 to 14.

Such releasing mechanism includes an electromagnet 41 and associated structure having a "Set" and a "Not set" positioning, together with means whereby such structure will be moved from the first to the second named one of said positionings responsive to effective or functional energization of said magnet in a manner which will be hereinafter more fully explained.

Circuit controlling or conditioning mechanism is associated with such structure for actuation thereby, which mechanism comprises the movable contacts 51, 53 and 55 and the stationary contacts 61, 63, 65 and 67.

The relative formation of the contacts 51, 53, 55, 61, 63, 65 and 67 is such that, during movement of said contacts 51, 53 and 55 (incident to rotation of a spindle 141 as will be hereinafter more fully explained) contact 51 will act to connect contacts 61 and 63 and contact 55 will act to connect contacts 65 and 67, at all times except when contact 53 serves to connect contacts 61 and 67.

The electromagnet 41 has applied thereto a main circuit or tripping winding 43 and a shunt loop or latching winding 45. The winding 43 is serially included in the main circuit MC. The contact 61 is connected to the main circuit at one side of the winding 43 and an end of the winding 45 is connected to the main circuit at the other side of the winding 43; the remaining end of said winding 45 being connected to the contact 67.

The windings 43 and 45 are so proportioned that when an intended shunt loop is serially connected between the contacts 61 and 67 (as in a manner which will be presently described) the current flow through one of said windings will substantially neutralize the effect upon said magnet 41 of the current flow through the other of said windings.

As shown in Fig. 1, the shunt loop SL comprises conductors serially connecting the auxiliary stations XS between the contacts 63 and 65. Each of said stations may be equipped with circuit controlling mechanism of any desired type, whereby the shunt loop is normally closed and may be interrupted when it is desired to cause activation

of the signal formulating mechanism of the station 21.

From the foregoing it will be apparent that when the circuit controlling mechanism associated with the releasing mechanism is positioned as indicated in Fig. 1, the contacts 61, 51, 63, the shunt loop SL, the winding 45 together with the contacts 65, 55 and 67 provide a current path in parallel with the current path through the winding 43. For convenience, the path through the winding 45 will be hereinafter at times referred to as the "latch path" and the path through the winding 43 will be referred to as the "trip path." Furthermore the electromagnet including winding 43 will, at times, be referred to as an "activating" or "initiating" magnet.

The electrical characteristics of the trip path should sufficiently resemble those of the latch path so that, throughout closure of both of said paths, effective energization of the magnet 41 will not result from abrupt changes in strength of current flow in the main circuit (such, for example, as those incident to signal formulating circuit closures or breaks).

Supplementary circuit controlling mechanism comprising the contacts 71, 73, 75 and 77 is associated with the releasing mechanism for actuation incidental to transfer of the contacts 51, 53, 55 from their normal or "Set" positioning as indicated in Fig. 1 to their abnormal or "Not set" positioning as indicated in Fig. 6.

Supervisory signaling or local alarm mechanism, diagrammatically indicated by the bell 78 operable from the battery 79, is connected to the contacts 73, 75 so that said bell will sound whenever the contacts 51, 53, 55 are in their abnormal or "Not set" positioning.

It may be assumed that additional stations such as 22, 23, 24 have signal formulating mechanism analogous to that of station 21, which formulating mechanism may be supplemented at any or all of such other stations by releasing mechanism therefor having respectively associated shunt loops.

In order to facilitate comprehension of this invention, the releasing mechanism of Figs. 8 to 14 will be now described in greater detail.

As previously explained, the electromagnet 41 contains the windings 43 and 45 and, for purposes of convenience in description, it may be assumed that the conductors 101, 103 are representative of the respective ends of the winding 43, and the conductors 105, 107 are representative of the respective ends of the winding 45.

An armature 111, pivotally supported at 112, is mounted in responsive relationship to the magnet 41; a clip 114 (see Fig. 12) being provided for suitably limiting the extent of the travel of the armature 111.

A retractile spring 116 (see Fig. 12) is applied to the armature 111 and may be supplemented by gravity for moving said armature away from the magnet 41 and yieldingly opposing its movement toward said magnet.

A detent member 131 (see Figs. 10 and 12) is fixed upon the shaft 133 and said shaft is journaled in the frame plates 135, 137 in such relation to the armature 111 that when said armature is in its retracted position the free end of said member 131 may be positioned within a recess in said armature (see Figs. 6 and 10) and engage a wall of such recess to thereby hold said shaft 133 against clockwise rotation. Furthermore the aforesaid relationship is such that when said armature is in attracted position, the wall of said

recess is withdrawn from the path of said detent member.

The shaft 133 is connected to the gear 145 through the pinion 143, said gear being journaled upon shaft 141 for rotation independently thereof. The ratio between said gear and pinion is such that each revolution of said gear 145 will cause three revolutions of said pinion 143. The three pins 147, 147, 147 are secured in the side of the gear 145 in equidistant relation and near the periphery thereof for a purpose hereinafter more fully explained.

The handle 151 and dial 153 are fixed upon the front end of the spindle 141. Said dial carries the indicia "Set" and "Not set" for observation in connection with the arrow 155 marked upon the frame. An insulating disc 57 is secured to the rear end of the spindle 141 and has fixed thereon the contacts 51, 53 and 55. The contacts 51 and 55 are substantially U-shape, having arms 20 extending along respective sides of the insulating disc 57 and interconnected through the intermediate portions extending through the slots 121 and 123 respectively. The contact 53 is applied to the rear side of the disc 57, and no corresponding contact is provided on the front side of said disc (see Figs. 13 and 14).

The sleeve 161 (see Fig. 12) is journaled upon the spindle 141 and has the gear 145 fixed upon one end thereof and the ratchet disc 163 fixed upon the other end thereof. Said disc has three equidistant notches formed in the periphery thereof.

An irregular plate 165 (see Figs. 9 and 12) is fixed upon the spindle 141, said plate being so formed as to provide an arm 167 for engaging the frame post 169 for limiting the counter-clockwise movement of said spindle, as well as providing the surface 171 for engaging the shaft 133 to limit the clockwise rotation of said spindle.

A ratchet dog 173 is pivotally attached to the plate 165 in such position that it may enter the notches in the disc 163. A spring 175 is applied between a pin 171 carried by said plate 165 and a pin 179 carried by said dog 173 for urging movement of said dog toward said disc 163.

The dog 173 is so formed and positioned that, during "Not set" conditioning of the spindle 141 (at which time the arm 167 of plate 165 engages the frame post 169) the free end of said dog is wedged between the post 169 and the walls of one of the notches of the disc 163, whereby the gear 145 is held against unintended movement.

A flat coiled spring 181 (best shown in Fig. 12) has the outer end thereof secured to the frame post 169 and the inner end thereof connected to the spindle 141, for urging rotation thereof in counter-clockwise direction.

An arm 183 moving with the armature 111 has the free end thereof situated in such relationship to the shoulder 185 formed in the outer surface of the dog 173 that, when the armature 111 is in attracted position, and the disc 163 is positioned as shown in Fig. 9 (the detent member 131 standing approximately as indicated by solid lines in Fig. 10) the free end of said arm 183 will be in the path of said shoulder 185, so as to prevent rotation of the spindle 141 from "Not set" to "Set" positioning. The aforesaid relative positioning further being such that the free end of the arm 183 will be withdrawn from the path of the shoulder 185, as just described, by retracted positioning of the armature.

The faces of the dog 173 and arm 183 which are adjacent when the releasing mechanism is in 75

- "Not set" position, are so relatively formed that the armature 111 will be prevented from assuming attracted position, and so that movement of said dog incident to rotation of the spindle 141 from "Set" to "Not set" position will cause the portion of said dog adjacent its pivot to so act upon the arm 183 as to move the armature 111 away from the magnet 41, irrespective of energization of said magnet.
- 10 A leaf spring 187, supported by the frame post 169, has the free end thereof resting upon the periphery of the gear 145 to serve as a stabilizing brake, for retaining said gear against accidental displacement during rotation of the spindle 141 from "Not set" to "Set" positioning.

As indicated in Fig. 11, a projection 191 extends into the path of the pins 147 carried by the gear 145, which projection may cooperate in any desired manner with the associated signal formulating device so that the rotation of the gear 145 incidental to movement of the spindle 141 from "Set" to "Not set" positioning will cause displacement of said projection 191 to thereby cause activation of the associated signal formulating mechanism.

For establishing desired connections between the contacts 73, 75 and 77, a contact 71 is carried by the insulating segment 81 which is pivoted at 83 and is connected through the crank pin 85 with the disc 57, as best indicated in Figs. 8 and 12, so that when said disc is in "Set" position, the segment 81 will bring the contact 71 into engagement with the contacts 73 and 77; and so that, when said disc is in "Not set" position, said segment will bring the contact 71 into engagement with the contacts 73 and 75.

Operation with differential windings

Under normal conditions, both the shunt loop 40 SL and the main circuit MC are closed (contacts 51 and 55 being positioned as indicated in Fig. 10). The current path through the main circuit divides at the main circuit connection with contact 61 and conductor 101 and at the main circuit connection with the joined ends of the windings 43 and 45. Due to the relative characteristics of the windings 43 and 45, the magnetic flux induced by current flow through said winding 43 opposes and cancels that induced by current flow through said winding 45, and vice versa; so that the magnet 41 has little, if any, attraction for the armature 111, and the spring 116 retains said armature 111 in retracted position.

If, now, the main circuit is alternately opened 55 and closed, as incident to formulation of a code signal, effective energization of the magnet 41 will not result, provided that the trip and latch current paths, through the windings 43 and 45, respectively, have electrical characteristics which 60 do not differ to an extent such as will cause the rate of change in the current flow in one of these paths (resultant from such breaks and closures of the main circuit) to differ sufficiently from that in the other of said paths, as to result in momentarily effective or functional energization of the magnet 41.

Whenever it is desired to cause the contacts 31 to act to formulate a signal in the main circuit MC, the shunt loop SL should be broken, as by 70 actuation of the circuit controlling mechanism at one of the stations XS. The breaking of loop SL will both cause current flow through winding 45 to cease and current flow through winding 43 to correspondingly increase, thereby effecting 75 functional energization of magnet 41.

Energization of magnet 41 will cause armature 111 to move to attracted position, where it will no longer retain detent member 131; thus permitting spring 181 to effect movement of the spindle 141 and parts carried thereby in counter-clockwise direction (as viewed in Figs. 9 and 11) until the arm 161 engages the frame post 169.

Rotation of the spindle 141, as just described, will carry the dial 153 from the position where its indicia "Set" registers with the arrow 155 to 10 the position shown in Figs. 9 and 11 where its indicia "Not set" registers with said arrow.

Furthermore, such rotation of the spindle 141 will rotate the detent member 131 in a clockwise direction from the position indicated by dotted lines in Fig. 10 to the position there indicated by solid lines, and will also rotate the disc 57 so as to change the relative positioning of the contacts of the circuit controlling mechanism from that indicated in Fig. 1 to that indicated in Fig. 6. 20

The turning of the gear 145 incident to the afore-described rotation of the spindle 141 will also cause one of the pins 147 to engage the projection 191 (see Fig. 11) associated with the signal formulating device, and thus effect initiation of operation of the signal formulating mechanism inclusive of intended rotation of the code wheel 32 and formulating actuation of the contacts 31.

The movement of the plate 165 during the rotation of the spindle 141, just referred to, will also carry the dog 173 to a position where it will engage the lower portion of the arm 183. Such engagement will force the armature 111 away from the magnet 41, and thereby assure retracted positioning of said armature notwithstanding the presence of any possible residual magnetism.

Because of the altered positioning of the contacts 51, 53 and 55 incidental to rotation of the disc 57 to "Not set" positioning, a current path 40 will be established between contacts 61 and 67, through the contact 53. In addition the portions of the contacts 51 and 55 shown by Fig. 13 will be withdrawn from the contacts 63 and 65, thereby completely isolating the auxiliary stations XS 45 and associated conductors from the main circuit MC and from the windings of the magnet 41.

From the foregoing it will be apparent that the breaking of the shunt loop SL causes effective functional energization of the magnet 41; which 50 energization, in turn, causes activation of the signal formulating device of station 21, disconnection of the auxiliary stations XS and the conductors connecting them from the station 21, and re-establishment of a current path through winding 45. Such re-established current path causes the resistance of the windings of the magnet 41, effective in the main circuit MC, to be restored to a value substantially identical to that effective prior to interruption of the shunt loop SL. 60

The movement of the segment 81, incidental to rotation of the disc 57 to the "Not set" position, carries the contact 71 into engagement with the contacts 73 and 75, thereby closing a circuit for effecting actuation of the bell 78, which will 65 thereafter act to sound a local alarm signal.

It will be evident that, after the contacts 51 and 55 have been withdrawn from engagement with the contacts 63 and 65, operability of the main circuit MC will be unimpaired by the establishment of accidental or malicious connections between the ground or a source of foreign electromotive force and any of the auxiliary stations XS or the conductors connecting them with the station 21.

The importance of this action will be more clearly realized if a concrete example is considered. For instance, assume that the system of Fig. 1 is employed for fire alarm service, that effective energization of the magnet 41 does not cause isolation of the shunt loop from the main circuit and that fires occur in the premises associated with stations 21 and 24. Further assume that such fires progress to an extent causing establishment of connections between the shunt loops respectively associated with such stations 21 and 24 and the earth, or between one of such loops and the earth and the other of such loops and an electric lighting or power circuit.

The circuit through the ground connections established with stations 21 and 24 would then form a shunt which would disable all intervening stations, such as the stations 22 and 23. A ground connection established with one loop and a foreign power circuit connection established with the other loop would result in current flow through the main circuit which would probably destroy that circuit or, at least, cause any protective devices included therein to act so as to disable the circuit.

From the foregoing it will be recognized that complete isolation of the auxiliary shunt loop SL from the main circuit MC renders said main circuit substantially immune from destruction or impairment of operability resultant from the aforesaid assumed ground and/or power circuit connections.

The importance of maintaining at substantially normal effectiveness in the main circuit the resistances of the windings of magnets of the various stations which correspond to the magnet 41 of station 21, even following the tripping of releasing mechanism, arises from the fact that variations in the resistance of the current path for the main circuit which might otherwise occur would tend to cause variations from the normal current strength inimical to most efficient manifestation of formulated code signals, especially in the event that the tripping or releasing mechanisms of numerous stations are concurrently in "Not set" condition.

Correspondingly, if main circuit conditions are such that the resistance of releasing mechanism windings forms a major portion of the total circuit resistance and there is a possibility that many of such mechanisms will be in "Not set" conditioning at the same time, it would be undesirable that the entire resistances of the windings of such mechanisms should be short-circuited, as the current flow in the main circuit might, in that event, objectionably increase.

After the current path through the shunt loop has been restored at the station XS from which a signal has been sent, the releasing mechanism may be restored by grasping the handle 151 and rotating it in clockwise direction until the surface 171 strikes the shaft 133. Such rotation will withdraw the ratchet dog 173 from the previously engaged notch of the disc 163 and carry it into engaging relationship with the walls of the next notch of said disc. As resetting pressure applied to the handle 151 is released, the urge of spring 181 will act (through spindle 141, plate 165, dog 173, disc 163, sleeve 161, gear 145 and pinion 143) to rotate the shaft 133 until the detent member 131 engages and is retained against further rotation by a wall in the recess of the now retracted armature 111, as already hereinbefore explained and indicated by dotted lines in Fig. 10.

Should restoration of the releasing mechanism

be attempted at a time when the current path through the shunt loop is interrupted, rotation of the handle 151 to move the dial 153 from "Not set" to "Set" positioning will be arrested, before the "Set" positioning is attained. This action 5 will be best understood by referring to Figs. 6, 8 and 9.

As indicated in Figs. 6 and 8, the contact 53 interconnects the contacts 61 and 67 when the releasing mechanism is in "Not set" positioning. 10 However, rotation of the spindle 141 for resetting the mechanism results in early withdrawal of such interconnection between contacts 61 and 67, and causes contact 51 to interconnect contacts 61 and 63 and contact 55 to interconnect contacts 65 15 and 67 (as indicated in Figs. 1, 2 and 3).

Such withdrawal of contact 53 causes cessation of current flow through latch winding 45, whereupon, at a time when the shunt loop is open or impaired, the entire current of main circuit MC 20 causes winding 43 to effectively energize magnet 41, so that armature 111 moves to attracted position. Such movement carries arm 183 into the path of the shoulder 185 so that when said shoulder is brought against the end of said arm, incident to ensuing rotation of the spindle 141, the rotation of said spindle and of the handle 151 and dial 153 will be arrested, thus indicating that the shunt loop is open and that it must be closed before the releasing mechanism can be fully 25 reset.

Should restoration of the releasing mechanism be attempted at a time when the shunt loop has been closed, current flow through winding 45 will be established through said loop following 35 withdrawal of contact 53 from engagement with contacts 61 and 67, so that said loop may take the place of said contact 53 in completing a current path through said winding 45 for neutralizing the effect of the current flow through winding 43. 40 Thus the spring 116 will be permitted to retain the armature 111 in retracted position whereby the spindle 141 may be completely restored or reset to its "Set" position.

Inter-magnet armature

For some situations and operating conditions it may be desirable to employ a latch path having electrical characteristics which differ in a substantial degree from those of the latch path 50 hereinbefore described. In such an event, releasing mechanism analogous to that indicated in Figs. 8, 9, 11 and 12 may be arranged for response to an armature playing between the poles of two electromagnets, as indicated in Figs. 2 and 6. 55

Referring to Fig. 2, the trip magnet 241 is so associated with the armature 211 that movement of said armature toward said magnet 241 will release the associated detent member 131 (see also Fig. 6). The latch magnet 242 is so associated with said armature 211 that energization of said magnet will oppose movement of said armature from its retracted position, with relation to trip magnet 241; which retracted position corresponds to the retracted position of armature 65 111 with relation to magnet 41 as indicated in Figs. 1 and 9.

It will be understood that the utilization of separate trip and latch magnets, as just referred to, will involve the displacement, with relation 70 to the armature, of the mechanism indicated in the lower part of Figs. 9 and 12, the use of a wider armature so that the magnet below the armature may be in a different vertical plane from that of the magnet above the armature, or 75

other modification along lines which will be clearly understood by those skilled in this art, to the end that the attraction of the armature by the latch magnet will oppose that by the trip magnet; the representations of such magnets in Figs. 2, 3, 4, 6 and 7 being diagrammatic in character.

The magnets 241 and 242 comprise the windings 243 and 245, respectively, which windings correspond with the windings 43 and 45 of the magnet 41 of Fig. 1.

It has been found that, at least in the utilization of a pair of bar magnets such as indicated in Fig. 2, having their remote ends interconnected by structure affording a magnetic path of low reluctance, it is desirable that the windings shall be so connected that the ends of the bars adjacent the armature 211 shall be of opposite polarity.

The windings 243 and 245 may be variously connected relative to the main and loop circuits and contacts. Such relationship may be in the manner shown in Fig. 2, in the manner shown in Fig. 3, or in a manner analogous to that indicated in Fig. 1, to meet various operating conditions, as hereinafter more fully explained.

Operation with inter-magnet armature

The operation of an embodiment of this invention utilizing an inter-magnet armature, as indicated in Figs. 2, 3 and 6, is similar to the operation of an embodiment utilizing differential windings (as hereinbefore more fully explained) except in respects as follows:

With parts positioned as indicated in Fig. 2, the attraction of the armature 211 by the magnet 241 is at all times overcome by the attraction of said armature by the magnet 242, owing to the extremely small gap between magnet 242 and said armature and a comparatively large gap between magnet 241 and said armature.

Throughout energization of the main circuit MC, and irrespective of variations in the strength of current flow through said circuit, it will be evident that the tension of spring 116 will be materially supplemented by the pull of magnet 242 in retaining the armature 211 in retracted position with relation to magnet 241.

Interruption of the current path through the shunt loop will cause deenergization of magnet 242 and increased energization of magnet 241, with resultant movement of the armature 211 to attracted position with relation to the trip magnet 241.

The releasing mechanism will thereupon act to start the signal formulating device and incidentally to move the armature 211 to retracted position relative to the trip magnet 241 as hereinbefore more fully explained.

When the shunt loop has been again closed and the releasing mechanism thereafter reset, the reenergization of magnet 242 will hold the armature 211 in retracted relationship to the magnet 241.

It will be apparent that the intermagnet armature embodiment of this invention is especially suited for use in situations where the releasing mechanism may be subject to extreme vibration or jarring or to severe mechanical shocks. Such embodiment is also well suited for situations wherein fluctuations in the current strength of the main circuit might cause effective functional energization of an electromagnet having two independent windings arranged as indicated in Fig. 1, as well as in situations wherein the resistance of the shunt loops is subject to variations so

great that, with either independent windings as indicated in Fig. 1 or parallel turn windings as indicated in Fig. 5, effective electromagnet energization might result from either extensive increase or extensive decrease in shunt loop resistance.

Due to the extreme advantage at which the magnet 242 acts over the magnet 241 in retaining the armature 211 in retracted position relative to said magnet 241, the inter-magnet armature embodiment of this invention is well suited to situations in which the electrical characteristics of the latch path differ materially from those of the trip path. For example, if the conductors for the shunt loop are subject to the shielding influence of enclosing metallic conduit, so that sudden surges may increase the current flow through the trip winding more rapidly than through the latch winding, the comparatively large gap through which the trip magnet 241 must act to withdraw the armature 211 from the attraction of the magnet 242 (through its relatively small gap) will prevent unintended tripping of the releasing mechanism. Under such circumstances unintended tripping of said mechanism might occur were the differential windings form employed.

Inter-locking armatures

As an example of the numerous possible embodiments of the broader aspects of this invention, an embodiment thereof is indicated in Figs. 4 and 7 in which a tripping magnet 441 controls a tripping armature 411 in a manner analogous to that of the control of armatures 35 111 and 211 of Figs. 1 and 2 by magnets 41 and 241, respectively.

Associated with tripping armature 411 is a latch armature 412 controlled by a latch magnet 442.

Windings 443 and 445 are associated with magnets 441 and 442 respectively.

Armature 412 is so inter-locked with armature 411 that throughout intended energization of magnet 442 said armature 412 will act to retain armature 411 in retracted position notwithstanding substantial disparity in strength of current flow in windings 443 and 445. Furthermore, the arrangement of parts is such that even should armature 411 be moved, responsive to the pull of magnet 441, a distance insufficient to trip the releasing mechanism, concurrent energization of magnet 442 will cause armature 412 to arrest the movement of armature 411 toward magnet 441 and force said armature 411 to its fully retracted position.

Trip and latch winding characteristics

As hereinbefore more fully explained, differential trip and latch windings may be connected as indicated in Fig. 1, so that, during "Set" conditioning of the releasing mechanism, current will flow through both of said windings and the current flow through one will substantially neutralize that through the other. With such conditioning, interruption of the shunt loop will then cause discontinuance of current flow through the latch winding and increased current flow through the trip winding for accomplishing effective energization of the trip magnet. Resultant action of the releasing mechanism will reestablish current flow through the latch winding so that the resistance interposed in the main circuit by the latch and trip magnet paths will not be substantially altered between "Set" and 75

"Not set" positionings of the releasing mechanism.

It will be apparent that inter-magnet armature, inter-locking armature and other embodiments of this invention may have corresponding windings connected in an analogous manner.

For operating conditions wherein it is deemed desirable that, when the releasing mechanism is in "Not set" condition, the electromagnet windings shall be short-circuited, connections such as indicated in Fig. 2 or in Fig. 3 may be substituted for those shown in Fig. 1.

With the indicated arrangement of Fig. 2, one end of the external shunt loop is at all times connected to one end of the latch winding, although the shunt loop is entirely disconnected from the main circuit when the releasing mechanism is in its "Not set" position. The other end of the latch winding is connected to contact 265, and the remaining end of the shunt loop is connected to contact 263. The portions of the main circuit which are connected to the ends of the trip winding are also connected to the contacts 261 and 267 respectively.

For situations where the shunt loop may be exposed to accidental connection with electro-motive force of other circuits or grounds, as hereinbefore more fully referred to, the connection indicated in Fig. 3 will be found preferable to that of Fig. 2, inasmuch as the shunt loop is here completely disconnected or isolated both from the main circuit and from the electromagnet windings when the releasing mechanism is in "Not set" position. Disconnection of the shunt loop from the main circuit is accomplished by withdrawal of contacts 51 and 55 from engagement with contacts 361, 363 and 365, 367 in a manner analogous to that explained in connection with corresponding contacts of Figs. 1 and 2. In the arrangement indicated in Fig. 3, neither the trip nor the latch windings are included in the external shunt loop connected to contacts 361 and 367 therefore tripping of the mechanism to "Not set" positioning causes complete disconnection of the shunt loop from the electromagnet windings.

As indicated in Fig. 3, the winding of the trip magnet is short-circuited when the releasing mechanism is in "Not set" positioning. This is accomplished by the utilization of contacts 371, 373 and 375 of supplementary circuit controlling mechanism which contacts correspond to the contacts 71, 73 and 75 of Fig. 1. Thus, when the releasing mechanism is in "Not set" condition, the contact 371 will interconnect the contacts 373 and 375, to which are respectively connected portions of the main circuit communicating with the ends of the trip winding.

To facilitate the testing of the shunt loop of Fig. 3 for open circuits either in the conductors thereof or at the stations XS therein, the contact 53 is arranged to short-circuit the ends of the shunt loop when the releasing mechanism is in "Not set" position.

Thus, in instances where the shunt loop system extends over a wide area and a station or stations XS have been operated, a caretaker of the system may advantageously make tests, in any well known manner, at various points of the loop circuit and thereby determine when all the stations XS and interconnecting conductors have been placed in closed condition whereby the releasing mechanism may be restored to its fully "Set" positioning.

For situations where it is desired to utilize

releasing mechanism constructed in accordance with certain features of this invention in association with a local current source (instead of using a local shunt loop), an arrangement such as that of Fig. 15 may be employed in which auxiliary stations XS15 are associated with signal formulating station 1521 through conductors whereby current flow from the source LS normally passes through conductors serially including the contacts of said auxiliary stations, the 10 comparatively high resistance test relay 1523, the trip coil 1543 and the latch coil 1545. As shown, the mechanism of said auxiliary stations is arranged so that actuation of the contact 1525 of any station will cause deenergization of the 15 latch coil 1545 and substantially increased energization of the trip coil 1543.

The contacts 1571, 1573, 1575 and 1577 correspond with the contacts 71, 73, 75 and 77 of Fig. 1, respectively; and the alarm bell AB is connected by suitable conductors in association with the contacts of relay 1523 and with contact 1575 so that said bell will be caused to sound in the event of current failure in the normal test current path as well as at all times when the releasing mechanism is in "Not set" condition.

While certain specific embodiments of this invention have been shown and described in considerable detail, it should be understood that this is illustrative only and for the purpose of making clear certain embodiments of the invention, and that the invention should not be regarded as limited to these details, or to any of them, except insofar as such limitations are included within the terms of the following claims, in which it is intended to claim all novelty inherent to this invention as broadly as is permissible in view of the prior art and to cover all of the generic and specific features of the invention herein described and all statements of the scope thereof which, as a matter of language, might be said to fall therebetween.

I claim:

1. Auxiliary starting mechanism for a code signal formulator comprising a trip magnet winding, a latch magnet winding, an armature normally held in an ineffective position and movable into an effective position upon energization of the trip magnet winding and de-energization of the latch magnet winding, activating means for the formulator having a normal set position and a not-set position, means operated by movement of the armature to effective position for operating the activating means to not-set position, and means for permitting manual resetting of the activating means only during energization of the latch magnet winding.

2. Auxiliary starting mechanism for a code signal formulator comprising a trip magnet winding, a latch magnet winding, an armature normally held in an ineffective position and movable into an effective position upon energization of the trip magnet winding and de-energization of the latch magnet winding, activating means for the formulator having a normal set position and a not-set position, means operated by movement of the armature to effective position for operating the activating means to not-set position, means operated by movement of the activating means to its non-set position for positively moving the armature toward its ineffective position, a manual resetting device for the activating means, and means to permit operation of the resetting device only during energization of the latch magnet winding.

3. Auxiliary starting mechanism for a code signal formulator comprising a trip magnet winding, a latch magnet winding, an armature normally held in an ineffective position and movable into an effective position upon energization of the trip magnet winding and de-energization of the latch magnet winding, activating means for the formulator having a normal set position and a not-set position, means operated by movement of the armature to effective position for operating the activating means to not-set position, a manual resetting device for the activating means, and means controlled by de-energization of the latch magnet winding during operation of the resetting device for preventing restoration of the activating means to set position.
4. Auxiliary starting mechanism for a code signal formulator comprising a trip magnet winding, a latch magnet winding, an armature normally held in an ineffective position and movable into an effective position upon energization of the trip magnet winding and de-energization of the latch magnet winding, activating means for the formulator having a normal set position and a not-set position, means operated by movement

of the armature to effective position for operating the activating means to not-set position, a manual resetting device for the activating means, and means operated by the armature, when the armature is in effective position during operation of the resetting device, for blocking movement of the resetting device. 5

5. Auxiliary starting mechanism for a code signal formulator comprising a trip magnet winding, a latch magnet winding, an armature normally held in an ineffective position and movable into an effective position upon energization of the trip magnet winding and de-energization of the latch magnet winding, activating means for the formulator having a normal set position and a not-set position, means operated by movement of the armature to effective position for operating the activating means to not-set position, a manual resetting device for the activating means, and a blocking arm movable with the armature 10 to prevent full movement of the resetting device if the armature is in its effective position during operation of the resetting device. 15

FRANK ROWLAND BRIDGES.
